ATTORNEY.

UNITED STATES PATENT OFFICE.

ALEXANDER DANIEL, OF CLEVELAND, OHIO.

WASHING MACHINE.

Application filed March 16, 1926. Serial No. 95,027.

The present invention relates to certain new and useful improvements in washing machines of the cylinder type, and has for its object to provide a clothes receiving cylinder or drum which embodies novel features of construction, whereby the water and suds or cleansing solution is caused to circulate through the interior of the cylinder in an effective manner as the cylinder is rotated.

Further objects of the invention are to provide a washing machine cylinder which is comparatively simple and inexpensive in its construction, which has rigid side walls and will not easily warp or lose its shape, and which can be handled in the same manner as the conventional cylinders which are in common use.

While one particular embodiment of the invention is shown and described in detail it will be understood that many modifications and changes can be made in the details of construction without departing from the spirit of the invention.

For a full understanding of the invention reference is to be had to the following description and accompanying drawings in which,

Figure 1 is a transverse vertical sectional view through a washing machine tub and cylinder which are constructed in accordance with the invention.

Figure 2 is a top plan view of the cylinder which has been lifted out of the tub.

Figure 3 is an enlarged sectional view through a portion of the peripheral walls of the tub.

Corresponding and like parts are referred to in the following description and indicated on all of the views of the drawing by like reference characters.

Referring to the drawings, which illustrate one of many possible embodiments of the invention, the numeral 1 designates a tub, which may be of any conventional construction, being shown as formed with a rounded bottom 1^a and as supported by the legs 2. Rotatably mounted within the tub is a cylinder A which is formed with circular end walls 3 and a curved side wall 4. One end of the cylinder is provided with the usual stub shaft 5 which may be received within a conventional bearing at one end of the tub, the other end wall of the cylinder being provided with a polygonal socket 6 which is adapted to receive and interlock

with a correspondingly shaped drive shaft projecting through the end wall of the tub. Any conventional power means can be used for turning the drive shaft to rotate the cylinder and it is customary in washing machines of this type to provide gearing for automatically reversing the direction of rotation of the cylinder after it has been turned in either direction a predetermined number of revolutions.

The cylindrical side wall of the cylinder is provided at suitable intervals with longitudinally extending slots 7. Arranged in each of the slots is a baffle member 8. The baffle members are radially disposed and project through the slots 7, being provided at their outer ends with lateral flanges 9 which project therefrom in opposite directions and overhang the respective sides of the slots. The flanges are in a spaced relation to the exterior of the cylinder and the baffle members 8 are shown as extending the full length of the cylinder and having their opposite ends secured to the end walls 3 of the cylinder. The cylinder can be conveniently formed from sheet metal and channel shaped strips of sheet metal can be used for forming the baffle members 8. The baffle members have a hollow formation and the edge portions of the side walls of the channel members can be bent laterally to provide the flanges 9. The inner ends of the baffle members may be formed in this manner so that there are no sharp corners or projections to catch upon and tear the clothes when the washing machine is in operation.

In order to provide for placing the clothes in the cylinder and removing them therefrom, an opening is formed in one side of the cylinder, said opening being normally closed by a door 10. The door may be secured in position in any suitable manner, although as shown on the drawings, it is provided at one edge thereof with lugs 11 which extend under the corresponding edge of the opening, the opposite edge of the door being provided with a latch 12 which is rotatable into and out of engagement with the opposite edge of the opening. When the cylinder is formed of sheet metal the edges of the longitudinal slots 7 therein may be returned, as shown at 13, around stiffening wires 14. Likewise, the edges of the flanges 9 of the baffle members 8 may be returned, as indicated at 15, around stiffening wires 16. The

free edges of the sheet metal parts are thus stiffened and at the same time any sharp edges which might have a tendency to injure the clothes being washed or fingers of the operator are eliminated.

When the cylinder A is mounted in position within the tub 1, as shown by Figure 1, the bottom of the cylinder is in a spaced relation to the correspondingly curved bottom 10 of the tub. The tub is partially filled with some suitable cleansing solution such as suds and water, and as the cylinder is rotated in either direction the projecting ends of the baffle members 8 and flanges 9 thereof serve 15 to catch portions of the cleansing fluid and force it to circulate upwardly through the slots 9 into the interior of the cylinder. The oppositely projecting lateral flanges 9 of the baffle members become alternately operative 20 as the cylinder is rotated in opposite directions, and as the cleansing fluid or solution is forced into the interior of the cylinder on one side of the baffle members 8 it can leave the cylinder through the portions of the slots 25 7 on the opposite sides of the baffle members 8. An effective circulation of the cleansing fluid or solution is thus maintained through the interior of the cylinder when the device is in operation and the portions of the side 30 wall 4 of the cylinder between the slots can be imperforate, thereby enabling it to have a rigid construction. As the cylinder is rotated in either direction the flanges 9 of the baffle members 8 tend to catch the cleansing fluid or solution between the bottom of the 35

tub and cylinder and force it into the cylinder through the portions of the slots 7 on one side of the baffle members 8. At the same time portions of the cleansing fluid already within the cylinder may leave the same through the portions of the slots 7 on the opposite side of the baffle members 8. In this manner a constant and effective circulation of the cleansing fluid is kept up through the interior of the cylinder, with the result 40 that the clothes or fabric within the cylinder is quickly and effectively cleansed.

Having thus described my invention what I claim as new and desire to secure by Letters Patent is,

A washing machine cylinder having longitudinal slots in the curved side walls thereof, hollow channel shaped baffles extending longitudinally of the cylinder on the interior thereof, and arranged with the sides thereof disposed in a substantially radial position and projecting outwardly through the slots in a spaced relation to the edges of the slots, and comparatively short oppositely projecting flanges at the outer ends of the sides of the channel shaped baffles, said flanges being in a spaced and substantially parallel relation to the exterior of the cylinder and co-operating with the outwardly projecting ends of the baffles to forcibly direct the cleansing fluid into the interior of the cylinder when the cylinder is rotated in either direction.

In testimony whereof I affix my signature.
ALEXANDER DANIEL.
